SLICING MACHINE

George R. Wood, Toronto, Ontario, Canada, assignor, by mesne assignments, to The Hobart Manufacturing Company, Troy, Ohio, a corporation of Ohio

Application July 29, 1932, Serial No. 625,727

15 Claims. (Cl. 146—102)

This invention relates to food slicing machines. The general object of the invention is to provide a novel type of slicer.

More specifically the object is to provide novel means for feeding an article past a knife edge to cause the latter to cut a slice.

Further, an object is to provide an abutment plate for the article normally disposed in the plane of the knife edge to guard the latter and movable away from the knife edge each time the article is fed towards the knife.

Still further, an object is to provide a novel mounting for a clamp on the article holding carriage.

15 Another object is to provide a novel one-piece casting in which is combined the base of the machine, the slice receiving tray, a motor and switch housing, and a knife supporting post.

Another object is also to provide a slice deflector arranged to house a portion of the knife pulley.

Still another object is to provide a combined one-piece sheet metal guard and housing for the knife.

25 Various other objects and advantages of the invention will be obvious from the following particular description of one form of mechanism embodying the invention or from an inspection of the accompanying drawings; and the invention also constitutes certain new and novel features of construction and combination of parts hereinafter set forth and claimed.

In the drawings:

Fig. 1 is an elevation of the machine from the 35 slice receiving side;

Fig. 2 is a top view of the machine;

Fig. 3 is an end view of the clamp and carriage with parts of the transverse feeding means in section;

40 Fig. 4 is a section on line 4—4 of Fig. 3;

Fig. 5 is an end view of the machine from the operator's side;

Fig. 6 is a section on line 6—6 of Fig. 3;

Fig. 7 is a section on line 7—7 of Fig. 6;

45 Fig. 8 is a detail of the abutment plate and its support;

Fig. 9 is a section on line 9—9 of Fig. 8;

Fig. 10 is a detail section of the abutment plate restoring means; and

50 Fig. 11 is a section on line 11—11 of Fig. 1.

Referring to the drawings in detail, the frame of the machine is a casting which is integrally formed with an inverted dish-like base section 10, a motor and switch housing 11, a knife post 55 or support 12 rising from the housing 11, and a

slice receiving tray 13 formed as a part of the base section and having an upright abutment 13' extending longitudinally of the machine. The motor 14 is inserted into housing 11 through the open bottom of the base 10 and is secured to a 5 plate 15 by screws 16, the plate 15 being fastened to the base by heavy screws 17 and 18. The knife post 12 journals the disk knife 19 therein, the knife having a flat face if desired, or a recessed or dished face as is usual in some machines, or the knife may be set at an angle as is known to those skilled in the art.

To guard the knife edge, a sheet metal stamped plate 20 is provided, this plate having an arcuate edge 21 concentric with the rear portion of the 15 knife edge. Extending to the left of this edge (as viewed in Figs. 1 and 2) the plate 20 is flat and acts as a closure for the open front of the housing 11 to the left of the knife. The plate 20 is formed with a concave portion 22 which extends rearwardly to cover and guard the back of the knife and is provided with a finger 25 secured by a thumb nut 26 to the bracket 27 fastened at the bottom to the top of the knife post 12. The bracket 27 at its upper end rotatably carries the 25 elements 28 for sharpening knife 19.

The motor 14 drives the knife through a belt connection 30 to the pulley 31 of the knife. The pulley is partially protected and covered by the concave portion 22 of plate 20, the post 12, and 30 the bracket 27, while the portion extending past the right side of post 12 (as viewed in Fig. 1) is housed and guarded in the concavity of a slice deflector 32 secured to the post 12. The front edge of the knife is guarded by a lower finger 35 guard 33 to which is fastened a slice support 34. The cutting arc of the knife is guarded by the arcuate edge of an abutment plate 36 which extends normally substantially parallel to and in the same plane as the cutting arc of the knife. 40 The abutment plate is provided with horizontal ribs 37 on the feed side to reduce the friction of the article being fed, this feature being particularly desirable when cutting cheese or the like. The plate extends vertically above the slice receiving tray 13 of the frame and rearwardly of the abutment 13', so that scraps dropping from the plate will fall on the receiving plate from which they may be conveniently removed.

The abutment plate 36 is supported from the 50 frame as follows:

Referring to Figs. 1, 8, 9, and 10, the back of the plate is provided with upper and lower bearing lugs 38 and 39 for rotatably receiving a round rod 40 which is rigidly carried at its lower end 55

by a generally horizontal crank arm 41 below the plate. Rod 40 carries two clutch collars 42 and 43 provided with interlocking teeth. Collar 42 is rigidly secured by a set screw 45 to the rod 5 while collar 43 is freely rotatable on the rod for adjustment purposes. Secured to collar 43 is the lower end of a coil spring 46 surrounding the rod 40, the upper end of the spring being secured to the upper bearing lug 38 rigid with the plate. 10 The spring urges the plate to rotate on rod 40 clockwise to hold the upper and lower ends of the arc portion of the plate in engagement with the stops 47 formed on the free slotted ends of the bracket 27 and the slice support 34 secured to 15 the lower finger guard 33.

In this position of the plate, the arc thereof is in the same plane as the cutting arc of the knife 19, thereby preventing the slightest possibility of the operator's fingers contacting the cutting arc 20 of the knife. The tension of the spring 46 may be adjusted by first lifting up on the collar 43 to demesh the teeth thereof from the teeth of collar 42 and then rotating it relative to collar 42 and rod 40 to more or less tension the spring. A 25 cover 48 is secured to the plate 36 for housing the rod 40, collars 42, 43, spring 46 and bearing lugs 38 and 39.

Crank arm 41 which rigidly carries the lower end of rod 40 is pinned to a vertical shaft 49 rotatably journaled in a hollow post 50 secured to the slice receiving part 13 of the frame at the end thereof remote from the knife. The lower end of the shaft 49 projects into the base and there has secured to it a horizontal arm 51, the free end of which is connected by a coil spring 52 to a washer 53. The washer 53 is clamped between the head of a bolt 54 and the bottom surface of the base, the bolt 54 securing the right hand post 55 to the base, this post and a similar post 55' at the other end of the base carrying between them the round, upper, rail 56.

Arm 51 is movable between adjustable screw stops 57 carried by an inverted U-bracket 58 secured to the under side of the base. Spring 52 45 acts on arm 51 to urge it together with attached crank arm 41 clockwise as viewed in Fig. 9 thereby tending to move rod 40 and the plate 36 connected thereto towards stops 47 and into the normal knife guarding plane.

50 Spring 52 is a light spring, considerably weaker in its resistance than spring 46 and will therefore yield much more readily than spring 46 when the abutment plate 36 is moved rearwardly of the knife plane towards the slice receiver. In effect, therefore, plate 36 may be thought of as substantially rigidly connected with rod 40 to move therewith against resistance of spring 52. The purpose of spring 46 is to always definitely hold the plate in knife guarding position when 55 there is no pressure exerted on the plate to move it rearwardly. The spring 46 is readily and conveniently adjustable to maintain the proper tension for this purpose.

65 Were spring 46 omitted and only spring 52 employed, the latter being the active resistance during operation of the machine and therefore continually stressed, might weaken after a while to such an extent as not to maintain the plate 36 against stops 47 and in the normal knife guarding plane. To adjust the spring 52 to increase its tension would require lifting the machine and turning it on its side to obtain access to the spring, whereas spring 46 may be adjusted merely by removing the cover 48. Another reason 70 why spring 52 should not be relied upon to hold

the plate against stops 47 is that it is desirable that this spring be very light so as to permit a slight pressure on the front of the plate 36 to move it rearwardly of the knife. Were spring 52 made heavy, the pressure required to move 5 plate 36 rearwardly would be such as to cause undue friction between the plate and the article contacting the plate.

Spring 46 thus continually exerts a force on the plate 36 for maintaining it in engagement 10 with stops 47 and takes the place of non-flexible means for adjusting the plate to engage the stops as the spring 52 weakens. Spring 46 in effect is a continuously self-adjusting device for maintaining the plate 36 against stops 47. The adjustment of the tension of spring 46 by rotation of collar 43 permits increasing the tension of the spring to take up any slack therein after the machine has been in extended use.

20 Plate 36 acts as a guard for the cutting arc of the knife and as an abutment for the article on the feeding carriage 60. The carriage is guided for reciprocation past the knife 19 and plate 36 by the aforesaid round rail 56 and a flat rail 61 on the base. The tray portion 62 of the carriage is two-sided, one of the sides being horizontal and the other vertical. A porcelainized or Monel metal plate 620 forms a non-corrosive lining for the tray portion.

25 To the exterior of the vertical side of the portion 62 is secured a round track 63 extending generally right angularly to the plane of the knife and plate 36. On the track 63 is slidably and rotatably mounted the clamp carrier 64 which has intermediate its width bearing lugs 35 65 at each end through which track 63 passes. The carrier has upper ears 66 to which is hinged by a removable hinge pin 67 the curved arm 68 which at its free end rotatably receives the rod 69 to which is fixed the combined pusher and 40 hold-down clamp 70 having a vertical face to serve as a pusher or last-slice clamp and a normally horizontal face to press the article against the horizontal side of the carriage tray 62 and against the supplementary underlying tray 71 45 which is secured by screws 72 to the lugs 73 of carrier 64 to move along with the carrier on the carriage 60.

50 The lower end of the carrier 64 has two bearing lugs 75 in which is eccentrically journaled the ends of a circular rack rod 76 formed at its lower end with rack teeth 77 meshing with a pinion 78 fully enclosed by a sleeve 780 projecting from the carriage except for an upper portion which engages the teeth 77. The turning axis of the 55 rod 76 in lugs 75 is eccentric to the center of the arc along which the teeth 77 extend in the direction of their width or the direction in which they follow the circular periphery of the rack rod so that turning the rod on bearing lugs 75 60 will demesh teeth 77 from pin 78 and move the rod bodily away from the pinion. The rod is normally held in a position in which the teeth 77 mesh with pinion 78 by the frictional contact of a screw 79 with the periphery of the rod. 65 However, a handle 80 on the end of the rod is provided for turning the rod 76 on its eccentric bearings to demesh the teeth 77 from pin 78 and permit the clamp carrier to be moved on the carriage away from the abutment plate and knife independently of pinion 78. When teeth 77 mesh with pinion 78 movement of the clamp carrier 70 away from the abutment plate and knife is not permitted because the pinion is part of a one-way drive which is made up as follows:

A stub shaft 81 extending outwardly from the vertical side of the carriage tray portion rotatably carries pinion 78 and the sleeve 82 to the base of which the pinion is fast. On the shaft 81 is also rotatably mounted the cam disk 83 and the handle 84, the entire assembly being retained on the shaft by the head of a screw 85 threaded into the free end of the shaft and so adjusted as to provide a moderate amount of friction between the outer side of the handle and the screw head and between the inner side of the handle and the contacting annular shoulder 86 of the shaft 81, this friction being desirable to prevent free turning of the handle. The handle is rigidly connected by pin 87 to the cam disk 83 which has three cam faces between which and the inside of sleeve 82 are located balls 88 which are pressed by coil springs 89 towards the narrow part of the space between the cam faces and the inside of the sleeve. When the handle is rocked counterclockwise, as viewed in Figs. 4 and 5, the balls clutch the cam and handle to the sleeve 82 rotating the latter and the pinion to move the rack 76 and the clamp carrier towards the plane of the abutment plate and the knife. When the handle is rocked clockwise, as viewed in Figs. 4 and 5, the balls ride freely along the inside of sleeve 82 and do not move the latter and the clamp carrier.

Return movement of the carrier is normally prevented because such movement, through rack 76, tends to rotate the pinion 78 clockwise, as viewed in Figs. 4 and 5, thereby urging the sleeve in a direction to wedge the balls 88 between the cam faces of cam disk 83 and the sleeve, thus locking the sleeve to the cam and handle against movement.

When the handle is moved counterclockwise, as explained above, it moves the clamp carrier towards the plane of the abutment plate. The article on the carriage is engaged with the plate 36 and is either clamped between the lower face of clamp 70 and underlying plate 71 or alternatively, if an end piece is clamped between the vertical side of the clamp 70 and the abutment plate. Hence upon movement of the clamp 70 towards the plate, the article gripped thereby will force the abutment plate rearwardly away from the plane of the cutting arc of the knife against the resistance of spring 52.

This condition is maintained as the carriage moves on its forward stroke with the article pressing on the plate and until the article leaves the arc of the abutment plate at which time the knife will have cut off a complete slice. When the article leaves the abutment plate, spring 52 returns the plate to normal knife guarding position which is maintained while the carriage is on the return stroke.

The plate 36 is moved rearwardly of the plane of the knife by pressure of the article a distance dependent on the thickness of slice to be cut by the knife. The transverse advance of the article on the carriage which determines the rearward movement of the plate in turn depends on the amount the handle 84 is rocked counterclockwise.

A gage device is provided to limit counterclockwise rocking of the handle in accordance with the thickness of slice desired. Any suitable mechanism may be used but for illustration a gage device disclosed in detail in application Ser. No. 537,313 which became Patent No. 1,939,030 on December 12, 1933, has been employed. This gage device in general comprises a threaded shaft 90 with a knurled knob handle 91 at one end.

The other end of the shaft is formed as a stop 92 for engagement with a lug 93 on the handle 84. The threaded portion of shaft 90 coacts with a threaded lug 94 forming part of a bracket 95 secured to the exterior of the vertical side of the carriage tray portion. The rotation of the shaft advances or retracts the stop end 92 and at the same time operates an indicator wheel 96 to indicate the thickness of slice to which the adjustment corresponds. The handle is movable between the fixed abutment 97 of the carriage and the adjustable stop 92.

In operation, an article is placed on the carriage tray 61 in contact with abutment plate 36 and between supplementary plate 71 and the clamp 70. The carriage being at the beginning of the forward stroke, the operator rocks handle 84 counterclockwise, as viewed in Fig. 4, into contact with stop 92, thereby through the one-way drive moving the clamped article in a direction to displace plate 36 against the force of spring 52 from the plane of the cutting edge of the knife a distance equal to the thickness of slice and as regulated by the gage shaft 90. The operator then pushes forwardly on the handle 84 to move the carriage past the plate 36 and the knife edge, the knife thereby cutting off a slice of the article. On the return stroke of the carriage, the spring 52 will have returned the abutment to guarding position and the article will slide past the plate without displacing it.

The plate 36 effectively serves as an end piece holder in cooperation with the vertical face of the clamp 70.

The plate 36 and its mounting may also be employed in the type of slicer having an automatic transverse feed combined with either an automatically or manually reciprocated carriage.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is as follows:

1. A slicing machine comprising a knife having an active cutting edge, an article abutment for substantially guarding said edge, a support, means for mounting the abutment on the support for displacement in a direction transversely of and to the rear of the cutting plane by pressure applied to the abutment, an article holder for supporting an article for movement towards the abutment to engage and displace the latter rearwardly of the cutting edge in a direction transverse to the plane of the knife and out of guarding position, the article holder and cutting edge being relatively movable past each other whereby after displacement of the abutment rearwardly of the knife by the article the aforesaid cutting edge may cut a slice from the article, means for returning the abutment to guarding position after the pressure of the article thereagainst is released and a device for variably regulating displacement of the abutment by the article in accordance with the thickness of slice to be cut.

2. A slicing machine comprising a knife having an active cutting edge, an article abutment normally occupying a predetermined position adjacent said edge, a support, means for mounting the abutment on the support for displacement rear-

wardly of the knife and of said predetermined position, means for resisting displacement of the abutment out of said predetermined position, an article holder for supporting an article, a clamp element movably mounted on the holder for engaging said article to move it towards the abutment for engaging and displacing the latter rearwardly of the knife and away from said predetermined position against resistance of said resisting means, the article holder and cutting edge being relatively movable past each other to cause the cutting edge to slice the article after the latter has moved the abutment rearwardly, and a gaging device for regulating movement of the article towards the abutment and corresponding displacement of the abutment rearwardly of the knife by the article in accordance with the thickness of slice desired.

3. A slicing machine comprising a knife, a guard masking the cutting edge of the knife, a displaceable mounting for the guard to permit the guard to be moved out of masking position with respect to the cutting edge and to thereby expose the latter, an article holder for traversing the guard and the knife, and a clamp element mounted on the holder for movement towards the guard to press an article on the holder against the guard and thereby displace the latter from knife masking position while the article holder is traversing the guard and knife to cause the latter to cut a slice from the article, and means for constantly resisting displacement of the guard away from masking position.

4. A slicing machine comprising a knife, a guard therefor, a displaceable mounting for the guard, means for resisting displacement of the guard from the knife guarding position, an article holder, said knife and holder being relatively movable past each other to permit the knife to cut a slice from the article, a clamp element for moving the article on the holder towards the guard to displace it against the resistance of said resisting means from guarding position whereby the knife may cut a slice from the article during relative movement of the knife and holder past each other.

5. A slicing machine comprising a knife, an article abutment plate extending normally along the cutting plane for guarding the knife, a frame; and means for movably mounting the plate on said frame comprising a shaft journalled on said frame, a crank arm connecting said shaft to said plate, a second crank arm connected to said shaft, and a resistant device connected to the second crank arm for resisting rotation of said shaft and consequent displacement of the abutment plate from the cutting and guarding plane.

6. A slicing machine comprising a rotatable knife with an effective cutting arc, a frame for rotatably mounting the knife, an abutment at the side of the cutting arc for guarding the latter, means for mounting the abutment on the frame for movement in a direction transverse to the cutting plane and so as to be displaceable in said direction and towards the rear of the cutting plane by pressure directly applied to the abutment, an article holding carriage mounted on the frame to reciprocate past the abutment and cutting arc and supporting an article for movement towards the abutment to apply pressure to the latter to move it to the rear of the cutting plane in aforesaid direction and away from guarding position to thereby expose the cutting edge to cut a slice from the article as the carriage reciprocates, and means for returning the abutment to

guarding position after the pressure of the article thereagainst is removed.

7. A slicing machine comprising a knife having an active cutting edge, guarding means for the knife edge including a guard portion in the same plane as, alongside of, and contiguous to the knife edge for masking the latter, means for mounting the guarding means for movement towards the rear of said plane to displace said guard portion to the rear of the knife edge plane and out of guarding position to expose the edge for cutting an article, means for resisting such displacement of the guarding means to tend to maintain the guard portion in guarding position, an article holder mounted to traverse the guarding means and knife and supporting an article for movement towards the guarding means to engage a portion of the latter and displace it against the resistance of said resisting means during travel of the holder to thereby move the guard portion to the rear of the knife edge plane whereby the latter is exposed to cut a slice from the article during the travel of the article holder.

8. A slicing machine comprising a rotary knife having a cutting arc, a guard for said arc, means for mounting the guard for displacement to and from a guarding position, means for resisting displacement of the guard away from said guarding position including a displacement resisting device connected to a stationary part of the machine, a second displacement resisting device of greater resistant strength than the first such device connecting the latter to the guard to substantially rigidly transmit the force of the first device to the guard, the guard being displaceable away from the guarding position substantially against resistance of the first device only, while the second device compensates for slack in the first device to urge the guard firmly towards the guarding position, and a stop for engaging the guard to limit its displacement towards the guarding position and thereby determining such guarding position.

9. The machine as defined in claim 8, each of said devices comprising a spring.

10. The machine as defined in claim 8, the second device being a torsionally wound spring, and the connection between the latter and the first device including a coupling with two relatively rotatable parts, one part connected to the spring and the other to said first device, rotation of the part connected to the spring varying the torsion of said spring to adjust its compensating action.

11. A slicing machine comprising a knife, a guard therefor, a displaceable mounting for the guard, means for resisting displacement of the guard from the knife guarding position, an article holder for supporting an article for movement towards the guard to displace the latter against resistance of said resisting means from guarding position, the article holder and knife being relatively movable past each other to cause the knife to cut a slice from the article while the guard is in the non-guarding position to which it has been displaced by aforesaid movement of the article.

12. A slicing machine comprising a knife having an effective cutting portion, an article abutment normally guarding said portion, a support, means for mounting the abutment on the support for displacement rearwardly of the knife and out of guarding position, means for resisting such displacement of the abutment, an article holder, the holder and knife being movable past each other, a clamp element mounted on a holder for movement toward the abutment, a driving member reciprocatably mounted on the holder, one way

driving connections between the driving member and said article engaging element to effect movement of said element toward the abutment upon reciprocation of said member, said element pressing the article against the abutment to displace the latter against resistance of said resisting means out of guarding position and into a position to the rear of the cutting plane of said knife for engaging the article while the article holder and knife are moving past each other to thereby permit the cutting edge to cut a slice from the article, and an adjustable gage device for variably regulating the stroke of the reciprocatable drive member to correspondingly regulate the movement of the clamp element and the article toward the abutment whereby the latter is positioned in accordance with the thickness of slice desired.

13. A slicing machine of the character described comprising a knife, an article holder, means for mounting the holder for reciprocating movement with respect to the knife, a clamp element mounted on said holder for movement toward the plane of the knife, a handle for said holder, means for mounting said handle on said holder in non-movable relation thereto in the direction of said reciprocating movement to provide for direct manual reciprocation of the holder, said mounting means also providing for relative movement between said handle and said holder in a direction different from that of the reciprocating movement, feed means for feeding said clamp transversely of said holder and toward the plane of said knife in response to said relative movement between said holder and said handle, said feed means being operable independently of movement of said handle in the direction of reciprocating movement, and a gage device for adjustably limiting the transverse movement of said clamp to variably adjust the feed of the article toward the knife plane.

14. A slicing machine of the character described comprising a knife, an article holder, means for mounting the holder for reciprocating movement with respect to the knife, a clamp element mounted on said holder for movement toward the plane of the knife, a handle for said holder, means for mounting said handle on said holder in non-movable relation thereto in the direction of said reciprocating movement to provide for direct manual reciprocation of the holder, said mounting means also providing for relative movement between said handle and said holder in a direction different from that of the reciprocating movement, feed means for feeding said clamp transversely of said holder and toward the plane of said knife in response to said relative movement between said holder and said handle, said feed means being operable independently of movement of said handle in the direction of reciprocating movement, and a gage device engageable with said handle for adjustably limiting its relative movement to variably adjust the feed of the article toward the knife plane.

15. A slicing machine of the character described comprising a knife, a guard having an edge in juxtaposition to and in the plane of the knife edge to guard and mask the latter, means for displaceably mounting said guard for movement in substantially parallel planes to and from guarding position, a stop for engaging the guard to limit its movement toward guarding position and thereby determining the guarding position of said guard, and resilient means acting on said guard tending to normally hold said guard in guarding position against said stop and substantially in the plane of the knife, said resilient means providing for yieldable displacement in said substantially parallel planes of said guard away from guarding position upon contact thereof with the work material.

GEORGE R. WOOD. 40
